COVERED SALAD BOWL

Sven-Eric Juhlin, Gustavsberg, Sweden, assignor to AB
Gustavsbergs Fabriker, Gustavsberg, Sweden

Filed Dec. 27, 1971, Ser. No. 212,873

Claims priority, application Sweden June 28, 1971

Term of patent 14 years

Int. Cl. D7—01

U.S. Cl. D7—17

THIE 11

THIE 2

FIG. 1 is a front, top and right side perspective view of a covered salad bowl with said cover in one position of adjustment showing my new design;

FIG. 2 is a front and top perspective view with said cover in another position of adjustment;

FIG. 3 is a perspective view with said cover and said bowl in disassembly;

FIG. 4 is a cross sectional front elevational view with said cover and said bowl in disassembly taken on lines 4a-4a and 4b-4b of FIG. 3.

I claim:

The ornamental design for a covered salad bowl, as shown.
